SELF-LOCKING HINGE

Michael J. De Leonardi, Valley Stream, N. Y.

Application August 25, 1949, Serial No. 112,365

2 Claims. (Cl. 16—138)

1

This invention relates to an improvement in hinges and is particularly adaptable to the type of hinge used on articles of luggage such as trunks and suitcases.

It is a purpose of the present invention to provide a hinge between the cover or lid of a trunk or suitcase and the main body thereof which will lock the cover or lid in an open position but which by the exertion of a slight force by the user may be readily released.

In suitcases, trunks and other similar receptacles it is common practice to provide a collapsible arm usually located at one of the ends of the receptacle which may be locked into position by the user to hold the cover or lid in fully open position. When it is desired to close the cover or lid, the user must release this arm from its locked position. The use of such an arm is necessary because many times the distribution of weight in the cover is such that it would ordinarily return to a closed position by force of gravity unless positively held in its open position. Such devices as these have two inherent disadvantages: Firstly, they require an extra part, increasing both the expense of manufacture and weight of the article to which they are applied and, secondly, they require the user to go to extra effort to release them when it is desired to close the receptacle. In the arrangement of my invention both of these disadvantages are overcome by the use of a self-locking hinge which increases the cost and weight of an ordinary hinge but slightly and which does not require the user to release a separate device.

The general object of this invention is, therefore, to provide a hinge particularly adapted to traveling cases such as suitcases and trunks but readily usable on various other boxes and receptacles which is self-locking when the cover or lid is in an open position but which is readily releasable by the user.

A further object of the invention is to provide means for locking a hinge in an open position and means for readily releasing it therefrom.

Further purposes and advantages of my invention will appear from the specification and claims herein. The invention is clearly illustrated in the drawings accompanying this specification in which

Fig. 1 is a perspective view of the hinge in open position;

Fig. 2 is a back or outside view of the hinge in closed position;

Fig. 3 is a front or inside view of the hinge in closed position;

2

Fig. 4 is a cross section on line 4—4 of Fig. 2; Fig. 5 is a perspective view of the locking strap; and

Fig. 6 is a perspective view of a leaf spring attached to the leaf of the hinge.

Each of the two leaves 10 and 11 of the hinge of my improved design is provided with a raised portion 12 spaced at a distance from the pintle 13 and preferably spaced equally distant from the lateral edges of the hinge. Each raised portion 12 has a pair of parallel slots 14 extending for appreciably the entire length of raised portions 12 and separated by the hinge body portion or strip 12a.

15 A locking strap 15 is provided for each hinge and is constructed as is most clearly shown in Fig. 5. Locking strap 15 has a back portion or web 16 connecting two side portions 17 forming a generally channel-shaped member. Side portions 17 extend beyond the ends of back portions 16, as may be seen in Fig. 4, and terminate in rounded end portions 18. Each rounded end portion 18 is provided near its center with a suitable hole or other means to receive the ends of a pin 19 which are secured to rounded end portions 18 in any suitable manner. Pins 19 thus form a transverse bar or link between opposite rounded end portions 18. Attached to each leaf 10 and 11 of the hinge at the end thereof near pintle 13 is a leaf spring 20 which is slightly bent or curved along a substantial portion of its length. Leaf springs 20 are firmly secured to their respective hinge leaves 10 and 11 to the end thereof adjacent pintle 13 by means of rivets 21 or in any other suitable manner. Leaf springs 20 are bent at their other ends to form semi-circular recesses 22. The length of springs 20 is such that recesses 22 are approximately positioned at the end of parallel slots 14 when springs 20 are riveted in place.

In assembling the hinge, locking strap 15 before pins 19 have been inserted therein is held in position so that locking strap end portions 18 fit into slots 14. Pins 19 are then inserted in rounded end portions 18 through suitable holes 23 (see Fig. 3) in the sides of raised portions 12 and pins 19 are clinched or otherwise secured in the holes in rounded end portions 18. Their position then is, as shown in Figs. 1 and 3, such that pins 19 ride between leaf springs 20 and the center portion 12a of raised portions 12. It now may be readily seen that locking strap 15 is slidably secured to the hinge and that rounded end portions 18 thereof are free to slide in parallel slots 14 as either of the hinge leaves 10 or 11

3

are rotated around pintle 13. However, when pins 19 reach recesses 22 in the ends of leaf springs 20, they are locked in that position unless enough force is exerted in a direction tending to move the hinge to its closed position to overcome the pressure of springs 20 against pins 19 and thus release pins 19 from recesses 22.

Side portions 17 of strap 15 are provided at their centers with notches 24 to permit locking strap 15 to fit closely over the portions of hinge leaves 10 and 11 which are bent around pintle 13 and thus to allow locking strap 15 to rest flatly against the main portion of the hinge when it is in its open position.

The hinge is provided with a number of suitable holes 25 by means of which it may be attached to the suitcase, trunk or other receptacle by rivets, screws, or in any other desirable and suitable manner.

It should be noted that the length of locking strap 15 should be such that pins 19 rest freely near the inner ends, that is, the ends near the pintle 13 of parallel slots 14 when the hinge is in its open position and that the length of back portion 16 of locking strap 15 which, as is pointed out above does not extend as far as the rounded end portions 18 of locking strap 15, should be sufficiently cut back from hinged end portions 18 to permit pins 19 to slide far enough in slots 14 to engage recesses 22 in springs 20. Further, the parts of the hinge should be so proportioned that when pins 19 engage recesses 22 of leaf springs 20 the hinge leaves 10 and 11 are substantially at right angles to each other.

It is obvious from the above descriptions that the pressure of leaf springs 20 is sufficient to hold the hinge in its open position against any force exerted on it such as the weight of the lid or cover itself, whether merely a plain lid or cover or one containing compartments for packing clothes or whatever articles are placed in the receptacle, but is not sufficient to hold the hinge in its open position when force is exerted at the unhinged end of the lid or cover by one desiring to close the suitcase, trunk or other receptacle.

In the example shown herein the proportioning of the parts is such that the hinge is self-locking when it is in its fully open position. It is obvious, however, that, if it is desired to limit the opening of a cover or lid so that it is less than the usual 90° angle, this may be accomplished by the hinge disclosed in the present specification merely by altering the length of the leaf springs 20 or the position of the recesses 22 therein, or by altering the length of locking strap 15.

I claim:

1. A self-locking hinge comprising, a pair of hinge leaves rotatably mounted on a pintle, each of said leaves having a central elevated portion, said portion being slotted with a pair of longi-

5

tudinally extending slots, spaced apart and defining between them a center strip forming part of said elevated portion, and a locking strap comprising spaced parallel side portions and a web portion, said side portions having end extensions extending beyond the respective extremities of said web portion, said end extensions being spaced apart to bridge said strips and to project into said slots respectively, leaf spring members mounted on the under side of each of said hinge members, each having a recess at one end, and means for mounting said spring members on said leaves respectively overlying the said strip portions of said leaves respectively, and each fixed at one end adjacent said pintle leaving the recessed end free, and pin means mounted between the extensions of the side portions of said locking strap at either end and disposed between the center strip of each leaf and the said spring member overlying it, whereby, when the leaves are bent at a predetermined angle the said pin means are engaged in the recesses of said spring members respectively.

2. A self-locking hinge comprising, a pair of hinge leaves rotatably mounted on a pintle, each of said leaves having a central elevated portion slotted with a pair of longitudinally extending slots spaced apart and defining between them a center strip forming part of said elevated portion, and a channel member comprising spaced parallel side portions and a web portion, said side portions having end extensions extending beyond the respective extremities of said web portion, said end extensions being spaced apart to bridge said strips and to project into said slots respectively, a pair of leaf spring members each having a recess at one end, and means for mounting said spring members on said leaves respectively with said members overlying the said strip portions of said leaves respectively, and each fixed at one end adjacent said pintle leaving the recessed end free, and pin means mounted between the extensions of the side portions of said channel member at either end of said member and disposed for sliding movement between the center strip of each leaf and the said spring member overlying it, whereby, when the leaves are bent at a predetermined angle the said pin means are engaged in the recesses of said spring members respectively.

MICHAEL J. DE LEONARDIS.
